DESIGN FOR A SHOPPING BAG OR THE LIKE

Isabel Manning Hewson, New York, N. Y.

Application February 3, 1942, Serial No. 105,604

Term of patent 7 years

To all whom it may concern:

Be it known that I, Isabel Manning Hewson, a citizen of the United States, residing in the city, county, and State of New York, have invented a new, original, and ornamental Design for a Shopping Bag or the like, of which the following is a specification, reference being had to the accompanying drawing, forming part thereof.

Fig. 1 is a perspective view of a shopping bag or the like showing my new design in partly unfolded position;

Fig. 2 is a front elevational view thereof in folded and closed position; and

Fig. 3 is an end elevational view thereof.

I claim:

The ornamental design for a shopping bag or the like, substantially as shown.

ISABEL MANNING HEWSON.
